CLAIM

The ornamental design for a pad for orthodontic bracket, as shown and described.

DESCRIPTION

FIG. 1 is a perspective view of the pad for orthodontic bracket showing my new design;

FIG. 2 is an enlarged perspective view of the pad on a bracket;

FIG. 3 is an enlarged top plan view thereof;

FIG. 4 is an enlarged front elevational view thereof;

FIG. 5 is an elevational view taken from the right side of FIG. 4, the left elevational view being a mirror image thereof;

FIG. 6 is an enlarged bottom plan view thereof; and,

FIG. 7 is an enlarged rear elevational view thereof.

The broken line showing in FIGS. 1 and 2 are for illustrative purposes only and forms no part of the claimed design.
